United States Patent Office

Des. 204,382

Patented Apr. 12, 1966

204,382

MULTIAPERATURE MAGNETIC CORE

David Nitzan, Palo Alto, Calif., and Joseph P. Sweeney,
Harrisburg, Pa., assignors to AMP Incorporated, Harris-
burg, Pa.

Filed Mar. 31, 1964, Ser. No. 79,272

Term of patent 14 years

(Cl. D26—1)

Fig. 1

Fig. 2

Fig. 4

Fig. 3

FIG. 1 is an end, top and side perspective view of a multiaperture magnetic core, showing our new design;

FIG. 2 is a top plan view, the bottom being substantially a mirror image thereof;

FIG. 3 is a side elevational view, the opposite side being substantially a mirror image thereof; and

FIG. 4 is an end elevational view, the opposite end being substantially a mirror image thereof.

We claim:

The ornamental design for a multiaperture magnetic core, as shown and described.
